(57) **CLAIM**

The ornamental design for a display screen with animated graphical user interface, as shown and described.

DESCRIPTION

The file of this patent contains at least one drawing executed in color. Copies of this patent with color drawing will be provided by the Office upon request and payment of the necessary fee.

FIG. 1 is a first image in a sequence of a front elevation view of a display screen with animated graphical user interface, showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof;

FIG. 15 is a fifteenth image thereof;

FIG. 16 is a sixteenth image thereof;

FIG. 17 is a seventeenth image thereof;

FIG. 18 is a eighteenth image thereof;

FIG. 19 is a nineteenth image thereof;

FIG. 20 is a twenty-earth image thereof;

FIG. 21 is a twenty first image thereof;

FIG. 22 is a twenty second image thereof;

FIG. 23 is a twenty third image thereof; and,

FIG. 24 is a twenty fourth image thereof.

The appearance of the image transitions between the images shown in FIGS. 1-24. The process or period in which an image transitions to another image forms no part of the claimed design.

(Continued)

The broken lines of uneven length show the display screen and form no part of the claimed design.
